UNITED STATES PATENT OFFICE.

ALVAH C. ROEBUCK, OF CHICAGO, ILLINOIS, ASSIGNOR TO THE ENTERPRISE OPTICAL MFG. COMPANY, OF CHICAGO, ILLINOIS, A CORPORATION OF ILLINOIS.

ARC-LAMP.

1,120,086.

Specification of Letters Patent.

Patented Dec. 8, 1914.

Application filed October 24, 1910. Serial No. 588,608.

To all whom it may concern:

Be it known that I, ALVAH C. ROEBUCK, a citizen of the United States of America, and a resident of Chicago, in the county of 5 Cook and State of Illinois, have invented certain new and useful Improvements in Arc-Lamps, of which the following is a specification.

This invention relates to that type of electric arc-lamps used in the lamp houses of optical projecting apparatus and the like, and in which the various adjustments of the lamp mechanisms are manually attained by operating shafts which extend outside the 15 walls of the lamp house. And the present improvement has for its object to provide a simple and efficient structural formation and combination of parts, with which the different vertical, angular or tilting, and 20 turning adjustments of the lamp mechanism are attained in an accurate and convenient manner, and with an avoidance of lost motion and undue friction between the parts.

A further object is to provide means 25 whereby a longitudinal adjustment of the upper lamp carbon, in relation to the lower lamp carbon, is attained in a ready and accurate manner, all as will hereinafter more fully appear.

30 In the accompanying drawings:—Figure 1, is a general side elevation illustrative of the present invention. Fig. 2, is a detail horizontal sectional view on line x , Fig. 1. Fig. 3, is a detail longitudinal sectional elevation on line x' , Fig. 4. Fig. 4, is a detail transverse sectional elevation on line x^2 , Fig. 2. Fig. 5, is a detail central vertical sectional elevation of the adjustable rack bars and their accessories. Fig. 6, is a detail horizontal sectional view on line x^3 , Fig. 5. Fig. 7, is a detail plan view with parts in section of the upper carbon holder and its supporting and adjusting means. Fig. 8, is a detail transverse section of the same on 45 line x^4 , Fig. 7.

Similar numerals of reference indicate like parts in the several views.

Referring to the drawings, 1 represents a portion of the track rails upon which the 50 carriage or turret base 2, of the arc-lamp is supported in a manner to permit of a longitudinal sliding adjustment. Said rails are secured to the base or bottom plate of the lamp house in the usual manner.

3 is a longitudinally arranged screw-shaft 55 journaled in a supporting bracket of one of the track rails 1, and having its screw-threaded portion engaged in the screw-threaded bore of a sleeve 4 on the turret base 2 aforesaid to impart longitudinal adjustment to the same upon the manual rotation of the shaft 3.

5, is a turret head having a vertically depending shank adapted for engagement in a corresponding socket sleeve 6 on the turret 65 base 2 to support the turret head 5 in place, and in a manner which admits of a turning adjustment of the turret head in attaining the proper longitudinal arrangement of the lamp mechanism carried thereon. As usual 70 in such type of connections the socket sleeve 6 will be provided with any usual and ordinary provision whereby its frictional engagement with the vertical shank of the turret head 5, can be adjusted as required. 75

7 is a shaft having a screw-threaded portion turning in a bracket lug on the turret base 2 and provided with a peripherally grooved head or enlargement at its forward end adapted for operative engagement 80 with a crank pin 8 on the underside of the turret head 5 to impart a turning adjustment to the same.

9 is a laterally arranged standard extending upward from the turret head 5 and carrying pivot screws or studs 10 and 11 in vertically separated relation as shown.

12 are a pair of ears arranged in longitudinal adjustment on the turret head 5 and adapted to carry the adjusting shaft herein- 90 after described.

13 is the block or housing in which the pair of oppositely moving rack bars of the carbon carriers are guided in their movements past each other in the various adjustments of the same.

14 is a depending arm on the block or housing 13 for connection with the intermediate connections as follows:

15 is a radius link pivoted at one end to 100 the upper pivot screw 10 of the aforesaid standard 9, and at its other end to the depending arm 14 above described.

16 is a bell crank lever pivoted to the lower pivot screw 11 of the aforesaid standard 9. The horizontal arm 17 of said lever is pivoted at its forward end to the aforesaid depending arm 14, and has a parallel

relation to the above described radius link 15 to act therewith as a secondary radius link, with the combined action of the two adapted to impose a vertical rise and fall 5 upon the block or housing 13 and the lamp parts carried thereon, without any tilting of the same from a normal plane. The vertical arm 18 of said lever is provided at its lower or free end with a lateral stud or its equivalent for operative engagement with an adjusting mechanism as follows:

19 is a longitudinal shaft guided in the aforesaid alined ears 12 of the turret head 5 and having a screw-threaded end portion 15 which engages in a similarly formed bore of one of said ears, so that a rotary motion of the shaft will effect a corresponding longitudinal travel of the same.

20 are a pair of separated collars on the shaft 19, between which the before described lateral stud on the vertical arm 18 of the bell crank lever 16 engages to receive an oscillatory adjustment therefrom.

21 and 22 are the rack bars, before referred to, and which are arranged and held in parallel and separated relation by guideways in the block or housing 13 aforesaid, and with their toothed faces opposed as usual.

23, is a pinion arranged between the rack bars 21 and 22 and having meshing engagement with the teeth of said rack bars, so that with a rotation of the pinion movement in opposite directions will be imparted to the respective rack bars.

24 is the carrying and operating shaft of the pinion 23, journaled in the block or housing 13 aforesaid and having operative connection with a secondary shaft 24' by a universal joint or connection preferably of the type shown in Figs. 5 and 6, and in which:

23' is a longitudinal extension fixedly secured to an end of the pinion shaft 24, and 45 formed at its free end into a sphere 23" having diametrically disposed studs 23''' as shown.

24" is a sleeve secured to the end of the shaft 24', and having a cylindrical socket 50 adapted to receive the sphere 23" aforesaid, and the circular wall of such socket is formed with longitudinal slots 24''' adapted for operative engagement with the studs 23''' aforesaid.

25 25 is a bracket head secured to the upper end of the rack bar 21 of the upper carbon carrier and formed with two pair of guide ears 26 and 27, each pair being in longitudinal alinement.

26 28 is an adjustable headstock provided with a longitudinal guide bar or rod 29 which has sliding engagement in orifices formed therefor in a pair of the guide ears 26, aforesaid. Said headstock also carries a 65 forwardly projecting bracket arm 30 to

which the upper carbon carrying arm of the lamp is adjustably secured as hereinafter more fully described.

31 is a longitudinal screw shaft journaled in the rearmost of the other pair of ears 27 aforesaid, with its screw-threaded forward portion screwing into a correspondingly formed tubular extension of the headstock 28, which in turn has sliding engagement in the forward ear of the aforesaid pair of ears 27 as shown. With such construction a rotation of the shaft 31 is adapted to impart adjustment to the headstock 28 lengthwise of the lamp house, to in turn effect an independent adjustment in a longitudinal plane 75 of the upper lamp carbon with relation to the lower lamp carbon in the operation of producing a perfect electric arc. The bracket arm 30 of the aforesaid headstock 28 is preferably formed in two parts or sections attached together with an insulating block 32 interposed at their point of connection to insulate the forward section of said arm and the parts carried thereon from the main portion of the lamp.

33 is the upper carbon carrying arm, the rear end of which is secured in a vertically adjustable manner to the forward end of the bracket arm 30 aforesaid by a pivot screw or bolt 34, and a clamping screw 35 attached to one part and having adjustment in a segmental series of holes 36 in the other part, the construction affording a limited adjustment between the parts, and in a vertical plane, as required.

37 is a cylindrical bushing flanged at one end and fitted in a correspondingly formed transverse orifice in the outer end of the carbon carrying arm 33 aforesaid, and held therein by one or more marginal screws 38, as shown, and which with a loosening of said screws permits of a turning adjustment of the said bushing and the holding clamp and upper lamp carbon carried thereby. Said bushing is formed with a central bore, one portion of which is circular and forms a guide for the stem of the carbon clamp, and the other portion of which is of a non-circular form and provides a guide for the middle non-circular portion of said carbon clamp to admit of a sliding movement between the parts and yet prevent any independent turning movement.

39 is the holding clamp for the upper lamp carbon 40, above referred to. In the present construction said clamp is provided with an end head 41 formed with a transverse opening for the reception of the lamp carbon 40; a central non-circular portion 42 adapted for sliding engagement in the non-circular portion of the orifice aforesaid of the bushing 37, and a screw-threaded end stem for engagement with a winged clamping nut 43, that has bearing on the side of the bushing 37 opposite to the end head 41, 120 125

and which in action is adapted to draw said head toward the bushing to firmly clamp the lamp carbon in place.

44 is a bracket head fixedly secured to the 5 lower end of the rack bar 22 of the lower lamp carbon carrier.

45 is a forwardly projecting bracket arm attached to the bracket head 44 with an insulating block 46 interposed at their point 10 of connection.

47 is the lower carbon carrying arm secured at its rear end to the forward end of the bracket arm 45 in a vertically adjustable manner by a pivot screw or bolt 48, and a 15 clamping screw 49 attached to one part and having adjustment in a segmental slot 50 in the other part, the construction being substantially identical with that of the upper carbon carrying arm 33 above described.

20 51 is a cylindrical flanged bushing fitting a transverse orifice formed therefor in the outer end of the lower carbon carrying arm 47 aforesaid. The said bushing is substantially identical with the bushing 37 of the 25 upper carbon carrying arm 33 before described, and is formed with a central bore, one portion of which is circular for the guidance of the stem of a carbon clamp, and another portion of which is non-circular for the 30 guidance of the middle non-circular portion of said carbon clamp to admit of a sliding movement between the parts without any independent turning movement between the same.

52 are marginal screws by which said bushing 51 is clamped in place after the required turning adjustment of the same has been effected.

53 is the holding clamp of the lower lamp 40 carbon 54 above referred to. Said clamp is substantially identical with the upper carbon clamp 39, above described, in its construction and arrangement and consists of an end head 5 having a transverse opening 45 for the reception of the lower lamp carbon 54; a central non-circular portion adapted for sliding non-rotatable engagement in the non-circular portion of the bore of the bushing 51 aforesaid, and screw-threaded stem 50 for engagement with the winged clamping nut 57, by which the lower lamp carbon is clamped in place.

58 and 59 are hook shaped ears carried by the respective bracket arms 30 and 45 aforesaid, in adjacent relation to the binding posts or screws 60 and 61 on said arms and by means of which the terminal ends of the

electric cables are electrically connected to the respective carbon carrying arms and carbons of the lamp. In the present construction the respective cables 62 and 63 are looped laterally under the aforesaid hook shaped ears 58 and 59 and are held thereby so that the normal bendings of said cables in the different adjustments of the lamp parts, is imposed on the cables between the entrance bushings 64 therefor in the wall 65 of the lamp house, and the aforesaid ears 58 and 59, and all bending strains on the terminal connections prevented.

The various operating shafts 3, 7, 19 and 24' heretofore described are of some length and are adapted to extend outside the rear wall 65 of the lamp house, and at their outer ends are provided with operating 70 wheels or handles for convenient operation by hand. And where such shafts have movement of any extent in angular planes, each shaft will be divided into sections which are connected together by any ordinary form of universal joint.

Having thus fully described my said invention what I claim as new and desire to secure by Letters Patent, is:—

1. An arc-lamp for optical projection apparatus, comprising an arc-lamp mechanism, a revoluble head carrying said mechanism and provided with a crank pin, a base carrying said head and provided with a pair of separated supporting ears one of which 85 has its bore screw-threaded, and a longitudinally disposed shaft provided with spaced collars for operative engagement with the aforesaid crank pin and having a screw-threaded end portion for operative engage- 90 ment with the screw-threaded bore of the supporting ear aforesaid.

2. In an arc-lamp for optical projecting apparatus, a housing carried by the lamp mechanism, a bracket mounted on said housing and provided with a series of guide ears, a headstock having a longitudinal guide bar moving in a pair of said guide ears and provided with a screw-threaded recess, and an adjusting screw shaft journaled 100 in another of said guide ears and screwing into the screw-threaded recess of the headstock, aforesaid.

Signed at Chicago, Illinois this 21st day of October 1910.

ALVAH C. ROEBUCK.
